Patented June 27, 1916.

Inventor

RICHARD R. LEE

By *Watson E. Coleman*

Attorney

UNITED STATES PATENT OFFICE.

RICHARD R. LEE, OF MERRIMAC, MASSACHUSETTS.

BARREL.

1,188,795.

Specification of Letters Patent. Patented June 27, 1916.

Application filed March 31, 1915. Serial No. 18,336.

To all whom it may concern:

Be it known that I, RICHARD R. LEE, a citizen of the United States, residing at Merrimac, in the county of Essex and State 5 of Massachusetts, have invented certain new and useful Improvements in Barrels, of which the following is a specification, reference being had to the accompanying drawings.

10 My present invention relates broadly to new and useful improvements in barrels of the stave type and has particular reference to an improved fastening means for holding the head in proper position within the chime 15 groove of the staves.

One of the principal objects of the invention is to provide a sheet metal retaining band which serves not only as a buffer for protecting the chimes against injury 20 from contact with foreign objects but also as a means for firmly and yieldably holding the head against withdrawal from the chime groove.

The above, and other incidental objects 25 of a similar nature, which will be herein-after more specifically treated are accomplished by such means as are illustrated in the accompanying drawings, described in the following specification, and then more particularly pointed out in the claim which is appended hereto and forms part of this application.

With reference to the drawings, wherein there has been illustrated the preferred embodiment of this invention, as it is reduced 35 to practice, and throughout the several views of which similar reference numerals designate corresponding parts, Figure 1 is a view looking down upon the upper edge 40 of the retainer; Fig. 2 is a vertical medial section taken through a barrel to which the retainer is applied; Fig. 3 is a composite view showing the two terminals of the band in open relation; Fig. 4 is a face view of the 45 band showing the terminals thereof interlocked; Fig. 5 is a detail perspective view of one terminal portion of the retainer; and Fig. 6 is a detail perspective view of the other terminal portion of the retainer.

50 The improved retaining band or hoop of this invention, which is best illustrated as an entirety in Fig. 1 of the accompanying drawings and designated by the letter A, is applied to the chimes 10 of an ordinary barrel 55 having a head 12 of conventional de-

sign which is seated within the chime groove 13.

The retaining hoop is preferably formed from a single strip of spring metal which is bent over a former to produce the annular 60 band or body portion 14, the diagonally extending spring flange 15 and the head engaging lip 16. The body portion 14 is provided at one end with an extension 14^a and said extension 14^a and the opposite terminal 65 of the body 14 are provided with oppositely disposed, transversely extending open slots 17 to produce connecting lugs 18, the slot in the extension 14^a being arranged in the upper margin thereof while the slot 17 in the 70 body 14 is positioned at the lower margin thereof. When the terminals of the body member are mated in the manner shown in Fig. 4 the two lugs interlock, thus holding the band in secure engagement against the 75 chimes. Apertures, indicated at 19 are formed in the terminals of the member 14 and are positioned to register with each other when the lugs are interlocked so that a screw or similar fastening means may be 80 employed, as an additional element for fastening the member 14 to the barrel.

The outer edge of the member 14 extends beyond the ends of the staves so that the spring flange 15, which extends inwardly toward the barrel head, and at an acute angle to the member 14, will not interfere with the chimes. The lip 16 extends at an approximate right angle to the body member 14 of the band and at an acute angle to the spring 90 flange, being adapted to flatly engage against the head of the barrel adjacent the periphery thereof.

From the foregoing description and particularly upon reference to Fig. 2 it will 95 now be readily observed that the body band 14 may now be easily and quickly attached to the barrel with the lip 16 disposed in engagement with the barrel head. Due to the resiliency of the spring flange, it is obvious 100 that the lip will be yieldably held at all times against the head with sufficient force to retain this member in seated position within the chime groove.

In reduction to practice, it has been found 105 that the form of this invention illustrated in the drawings, and referred to in the above description as the preferred embodiment is the most efficient and practical; yet realizing that the conditions concurrent 110

with the adoption of this device will necessarily vary, it is desirable to emphasize the fact that various minor changes in the details of construction, proportion and arrangement of parts may be resorted to, when required, without sacrificing any of the advantages of this invention, as defined by the appended claim.

What is claimed is:—

- 10 The combination with a barrel having a chime groove and a head seated therein, of a retaining hoop formed from a single strip of sheet metal shaped to produce an annular band which is adapted to embrace the
- 15 chimes on the outer face thereof, an angularly extending, inwardly directed annular spring flange formed on the outer edge of the band and bridging the chime of the barrel, and an annular head engaging loop
- 20 formed on the inner face of the flange and extending toward the band and in a plane

approximately at right angles thereto, one end of the annular band being provided with an extension, said extension and the opposite end terminal of the band being provided with oppositely directed transversely disposed open slots, the slot of the extension being arranged in the upper marginal portion thereof and the slot in the opposite terminal of the band being arranged in the lower marginal portion thereof, said slots affording interlocking lugs, the opposite terminals of the band inwardly of the slots being provided with openings adapted to register for the passage therethrough of an anchoring medium.

In testimony whereof I hereunto affix my signature in the presence of two witnesses.

RICHARD R. LEE.
